UNITED STATES PATENT OFFICE.

CHARLES BOHN CROFFORD, OF VICKSBURG, MISSISSIPPI, ASSIGNOR OF
ONE-HALF TO A. E. ENOCHS, OF SAME PLACE.

SHAVING-CUP.

SPECIFICATION forming part of Letters Patent No. 625,719, dated May 23, 1899.

Application filed July 25, 1898. Serial No. 686,811. (No model.)

To all whom it may concern:

Be it known that I, CHARLES BOHN CROFFORD, a citizen of the United States, residing at Vicksburg, in the county of Warren and

5 State of Mississippi, have invented certain new and useful Improvements in Shaving Companions; and I do declare the following to be a full, clear, and exact description of the invention, such as will enable others skilled 10 in the art to which it appertains to make and use the same.

My invention relates to a portable or collapsible shaving outfit for travelers; and the object is to provide a simple, compact, and 15 convenient device for this purpose.

To this end the invention consists in the construction, combination, and arrangement of the device, as will be hereinafter more fully described, and particularly pointed out in the 20 claim.

The accompanying drawings show my invention in the best form now known to me; but many changes in the details might be made within the skill of a good mechanic without departing from the spirit of my invention 25 as set forth in the claim at the end of this specification.

The same reference characters indicate the same parts of the invention.

30 Fig. 1 is a perspective view of my improved shaving companion. Fig. 2 is a longitudinal section of the same. Fig. 3 is a perspective view showing the cup extended, the brush in it, and the mirror set up for use. Fig. 4 is a detail view of the cap or cover.

35 1 denotes the bottom flange, to which the lower conical section 2 is fixed, and 3 the upper corresponding conical section, which telescopically encompasses the lower section.

40 The bottom flange 1 is formed with an annular circumferential rabbeted recess 4, which forms a seat for the lower edge of the upper section 3 when collapsed.

45 5 denotes the cap or cover, in the top of which is secured a mirror 6, and its bottom face is provided with an annular flange 7, which is snugly encompassed by the upper edge of the section 3, and 8 denotes a spring-wire bracket pivoted in the lug 9, fixed to the

bottom face of the cap 5, and which may be 50 extended, as shown in Fig. 3, to support the mirror in a vertically-inclined position when in use.

10 denotes a radial sleeve or socket fixed to the outside of the upper section 3 to receive 55 the removable tubular handle 12, and 13 denotes the brush-head, formed with the cylindrical shank 14. The socket 10 is formed with a circumferential groove 15 and the inner end of the tubular handle with an integral spring-tongue 16, the free end of which is turned inwardly to form a lip 17, which engages the groove in the socket to retain the handle in place and prevent its accidental displacement. The inner end of the tubular 60 handle is formed with an internal shoulder 18, against which the end of the brush-shank abuts, while the spring-tongue engages the front end of the brush-shank to retain it in place when the brush is in use. 70

The lug 9 is formed with a notch 19 to receive one of the arms of the spring-wire bracket to retain it in place when folded, as shown in Fig. 4.

Having thus fully described my invention, 75 what I claim as new and useful, and desire to secure by Letters Patent of the United States, is—

As an improved article of manufacture, a 80 shaving companion, comprising the lower conical section 2 having the bottom flange 1 fixed thereto; the upper corresponding conical section 3 telescopically encompassing said lower conical section; the cover 5; the annular flange 7 encompassing the upper edge of the 85 upper conical section 3; and the sleeve or socket 10 projecting radially from said conical section 3; and the tubular handle engaging said sleeve or socket 10, substantially as specified. 90

In testimony whereof I have hereunto set my hand in presence of two subscribing witnesses.

CHARLES BOHN CROFFORD.
